DESK MEMORANDUM PAD

Filed May 2, 1921

By Whittmore Hubbard Whittmore
+ Belknap
Attorney.

UNITED STATES PATENT OFFICE.

HENRY THOMAS PLATZ, OF ASHLAND, OHIO, ASSIGNOR TO MEMO MANUFACTURING COMPANY, OF DETROIT, MICHIGAN, A CORPORATION OF MICHIGAN.

DESK MEMORANDUM PAD.

Application filed May 2, 1921. Serial No. 466,000.

To all whom it may concern:

Be it known that I, HENRY THOMAS PLATZ, a citizen of the United States of America, residing at Ashland, in the county 5 of Ashland and State of Ohio, have invented certain new and useful Improvements in Desk Memorandum Pads, of which the following is a specification, reference being had therein to the accompanying drawings.

10 The invention relates to desk memorandum pads and has for its object the obtaining of a construction in which the memoranda may be preserved so as to be accessible for quick reference. To this end the 15 invention consists in the construction as hereinafter set forth.

In the drawings:

Figure 1 is a sectional side elevation of the machine;

20 Figure 2 is a sectional end elevation thereof.

A and A' are side members of a frame, being preferably formed of sheet metal stamping, and B is a base member for connecting said side members by suitable means such as tongues C depending from the side members and passing through slits in the base. D are rubber feet secured to the base to support the same upon the desk without 25 injury to the finish. E is a plate extending between the sides A and A' a short distance above the base and preferably slightly inclined to form a convenient writing desk. This plate may also be formed of sheet metal 30 and secured to the sides by tongues or similar devices. F and G are paper roll holders which are mounted to extend between the sides A and A' of the frame. H, I and J are idler rolls which also extend between the 35 sides of the frame and form guides for the paper strip. Each of the rolls F and G preferably comprises a tube of wood, or other suitable material, K on which the paper roll is placed, the flanges L at opposite ends of 40 said roll, a shaft M passing through said tube, a crank N attached to one end of the shaft, and a clamping screw O at the opposite end of said shaft. The flanges L are formed with out-turned thimble portions P, 45 which are sleeved upon the shaft M and which engage apertures in the sides A and A' to form journals for the roll. Surrounding the thimbles P the flanges L are inwardly embossed, as indicated at Q, to bear 50 against the ends of the tube K and are out-

wardly embossed at R to bear against the sides of the frame. The clamping screw O has the head thereof engaging one of the thimbles and thus by tightening this screw, a clamping pressure is exerted upon this 60 thimble and through the medium of the shaft M upon the thimble at the opposite end of said shaft, clamping the embossed portions Q against the ends of the roll and forming a driving engagement therewith. 65

The idler rolls H, I and J are each formed by a tie rod S extending between the sides of the frame and secured thereto by clamping screws T, while sleeved upon said tie rod is the tubular roll. 70

With the construction described, in use, a roll of paper is placed upon one of the rolls F or G and the end thereof engaged with the other roll, after first being passed over and about the idler rolls H, J and I. 75 This will draw a portion of the paper strip across the top of the table or plate E in a position where the memoranda is successively placed upon the exposed portion of the strip and by turning the cranks N, the 80 paper is advanced so as to expose another portion. This may continue for as long a period as desired and at any time reference may quickly be made in memorandum on the strip by reeling the paper on the opposite 85 roll. Thus there is no danger of losing or misplacing any memoranda, nor is there any difficulty in referring to the same.

What I claim as my invention is:

1. A desk memorandum pad comprising 90 a frame including a table or writing tablet, a pair of paper holding rolls journaled in said frame, one of said rolls being located above said table, idler rolls also journaled in said frame and arranged to guide the paper strip extending from one roll around and over said writing tablet and to the other roll, and means for rotating said rolls to wind the strip from one to the other. 95

2. A desk memorandum pad comprising a 100 frame having sheet metal sides and a plate extending therebetween forming a table or writing tablet, a pair of paper-holding rolls journaled in said sides and extending therebetween, the paper strip from one of said rolls passing around and over said tablet to the other of said rolls, each of said rolls comprising a shaft, a sleeve thereupon, end flanges abutting against said sleeve provided with thimbles also sleeved upon said shaft 105 110

and together therewith passing through bearings in said frame, a crank secured to said shaft at one end thereof, and a clamping screw engaging the opposite end of said shaft and bearing against one of said thimbles to exert clamping pressure thereon.

3. A desk memorandum pad comprising a frame having metallic side plates, a connecting bottom plate and a plate constituting a writing tablet, a pair of paper holding rolls journaled in said frame and extending therebetween, idler rolls extending between the sides of the frame, and tie rods for the sides of said frame extending through said idler rolls and forming journals therefor, each of said paper-holding rolls comprising a sleeve, a shaft insertable therethrough, end flanges for said sleeve having outwardly extending thimble portions fitting upon said shaft and together therewith extending through bearings in the sides of said frame, inwardly embossed annular portions on said flanges for bearing against the ends of said sleeve and outwardly embossed annular portions on said flanges for bearing against the sides of the frame, a crank attached to one end of the shaft, and a clamping screw engaging the opposite end of the shaft and bearing against one of said thimbles to exert clamping pressure on both of said flanges against said sleeve.

4. A desk memorandum pad, comprising a frame including a table or writing tablet, a pair of paper holding rolls journaled in said frame, with the paper strip leading from one roll over said table to the other roll, movable means for tensioning said strip, and

guiding the same upon one of said rolls, and means for winding said rolls to reel the paper from one to the other and passing the same across said table.

5. A desk memorandum pad comprising a frame, a plate carried by said frame and forming a table or writing tablet, a pair of paper holding rolls journaled in the sides of said frame, the paper strip from one of said rolls passing around and over said tablet to the other of said rolls, each of said rolls comprising a shaft, a sleeve thereupon, end flanges abutting against said sleeve provided with thimbles also sleeved upon said shaft and together therewith passing through bearings in said frame, means secured to said shaft for rotating the same, and means engaging said shaft and bearing against one of said thimbles to exert clamping pressure thereon.

6. A desk memorandum pad comprising a frame including a table or writing tablet, a pair of paper holding rolls journaled in said frame, one of said rolls being located above said table, idler rolls at the opposite ends of said table, one of said idler rolls being above said table, the other of said rolls being below said table, said idler rolls being adapted to guide the paper strip extending from one of the paper holding rolls, around and over said writing tablet and to the other paper holding roll, and means for rotating said paper holding rolls to wind the strip from one to the other.

In testimony whereof I affix my signature.

HENRY THOMAS PLATZ.
